UNITED STATES PATENT OFFICE.

OTTO WIENCKE, OF LEIPZIG, GERMANY.

ROTARY PLATE-LIKE SCREEN.

Application filed June 22, 1928, Serial No. 287,452, and in Germany December 1, 1928.

The present invention has for its object to provide a rotary plate-like screen for materials to be sifted. A characteristic feature of said rotary-screen consists in that the outer periphery or rim of the plate protruding above the screen-surface is arranged as a belt-pulley provided with a slot or slots situated above the screen-surface. A belt guided on one or more guide- or drive-rollers 5 is moved around said belt-pulley in such a manner that the slot or slots of the upwardly protruding periphery or rim are covered by said belt up to the point where the belt is raised from the guide- or drive-rollers and 10 the slot or slots are opened for discharging the material of coarser grain which remains on top of the plate-like screen.

A practical embodiment of the invention is represented in the accompanying drawings, in which

Fig. 1 is a vertical section (through the line I—I of Fig. 2, looking in the direction of the arrows) and

Fig. 2 is a top plan of the plate-like screen.

Figs. 3 and 4 show in vertical section and in top plan a modification of the screen and

Figs. 5 and 6 show in vertical section and in top plan another modification of the same.

Fig. 7 is a detail end view of the disc ar-

anged with noses or pins.

As clearly seen from Figs. 1 and 2 the rotatable plate-like screen *b* is fastened on the driven shaft *a* and arranged with a periphery or rim *c* protruding above the screen-surface.

In this periphery or rim *c* a slot or slots *d* is or are arranged directly above the screen-surface. Said periphery or rim *c* protruding above the screen-surface is formed as a belt-pulley around which a belt *e* is moved, 35 the latter being guided over a roller *f*, Fig. 2, in such a manner that the slot *d* arranged in the periphery or rim *c* is covered or closed and is only open at the periphery or rim *c*, viz., from the point of separation of the

belt from the belt-pulley—see point A—up to the point of the belt again touching the pulley—see point B. The material of coarser grain resting on the plate-like screen *b* and not sifted through is thrown by centrifugal force through the part of said slot *d* not covered by the belt *e* and drops into the receiver or vessel *g*, whereas the material of fine grain is sifted into the collecting-vessel *h*.

The supply of material to be sifted to the

plate-like screen *b* is caused by an endless band *k* so arranged that the material is supplied to the screen tangentially and across the width of the sifting-surface. The speed of the endless band *k* is so proportioned that the speed of the material falling onto the sifting-surface is substantially equal to the horizontal speed measured at the radial center of the rotating sifting-surface.

As seen from Figs. 3 and 5, the driving-shaft *l* of the plate-like screen *b* can be arranged to slant at a suitable angle to the vertical in order that the material to be sifted may be received from the feed supply band on the one side by a rising screen-surface and discharged into vessels on the other side by the descending surface.

The rotatable plate-like screen can be formed, as shown in Figs. 4 and 6, by two or more concentrically arranged disc-rings *m*, *m*¹, suitably secured together and supported from the drive shaft *l*.

In case the plate-like screen *b* is subdivided into several disc-rings, the endless-band *k* can be arranged in such a manner, that the latter is seated above the disc-ring situated nearest to the centre, as represented in Fig. 4 in plan. The speed of the endless-band *k* is such that the material to be sifted is fed with a speed substantially equal to the horizontal speed in the radial middle of the disc-ring nearest to its centre.

For the purpose of adapting the supply-speed of the material to be sifted to the surface speed of a plurality of rings, the endless supply-band *k* can be subdivided, as seen in Figs. 5 and 6. The two endless-bands *k*¹, *k*² are separately driven so that the speed of the material leaving said two endless-bands may be adapted to the surface speeds of the several screen-rings, as before explained.

To ameliorate the sifting-procedure and to provide a cleansing procedure, the plate-like screen *b* can, during its rotary movement, be subjected to a vibratory movement. For this purpose there is provided, as shown for instance in Figs. 3 and 5, a ring-surface *o* at the lower surface of the plate-like screen, said ring-surface resting on a disc *q* arranged with noses or pins *p* (Fig. 7) or on an eccentric disc, so that the plate-like screen is subjected to a vibratory or jarring movement upon the rotation of said disc.

As clearly seen in Figs. 3 and 5, the bearings carrying the shaft of the pin-disc are

yieldingly suspended for the purpose of ensuring a firm contact of the pin or eccentric disc with the ring.

Without in any way leaving the scope of the present invention the disc *q* can be arranged as a round disc and projections or notches can be arranged on the ring arranged on the plate-like screen, for the purpose of obtaining a vibratory movement of said screen.

For insuring a better sifting-effect for the material to be sifted and passing through the plate-like screen, the upper surface of said screen can be dished somewhat, as represented in Figs. 3 and 5.

As indicated in Figs. 4 and 6, the screen-apertures *t* (shaped as slots) are concentrically arranged in the disc-ring *m* situated towards the middle of the screen *b* and radially arranged in the disc-ring *m*¹ situated towards the outer periphery, for the purpose of increasing the sifting-effect.

For a better distribution of the sifted material falling down into the collecting receptacle or bunker *h*, scrapers *u* are for example arranged radially on the lower side of the plate-like screen, by which the sifted material fallen down into the collecting-receptacle or bunker *h* is distributed. If it is intended not to collect the sifted material in a receptacle or bunker, but to deliver it to any suitable place, a stationary bottom *v* can be provided below the rotatable plate-like screen, Fig. 5, and provided with an aperture *w*. Below said aperture *w* is arranged an endless conveyor-band *x*, for supplying the material sifted through the plate-like screen by the scrapers *u* radially arranged on the screen through the aperture *w* of the bottom *v* and onto the conveyor-bands *x*. In this manner the advantage is also obtained that the height of fall of the sifted material is limited as much as possible.

As shown in Figs. 4 and 6, a spouting device *y* can be arranged at the outer periphery of the plate-like screen and situated within the covering belt *e* in advance of the point of discharge of the material of larger grains in such a manner that a water-jet is thrown in an opposite direction to the rotation of the screen and against the material resting on the plate-like screen for the purpose of washing the sifted material before its delivery and of rinsing the material of larger grain not sifted together with the water through the slot-opening *d* at the periphery of the plate-like screen, whereby the material to be delivered is essentially improved.

What I claim is:

1. A device of the character described comprising, a screen, means for rotating the screen, a rim projecting upwardly from the periphery of said screen and being provided with slots adjacent the upper surface of the screen, a belt-pulley located outside the cir-

cumference of the screen, and a belt guided around said rim and said pulley, said belt being adapted to cover the slots in the rim throughout part of their rotation and to uncover said slots at another part.

2. A device of the character described comprising, a screen, means for rotating the screen, a rim projecting upwardly from the periphery of said screen and being provided with slots, a belt-pulley located outside the circumference of the screen, a belt guided around said rim and said pulley, said belt being adapted to cover the slots in the rim throughout part of their rotation and to uncover said slots at another part, an endless supply-band for delivering material tangentially onto the screen, and means for driving the said band.

3. A device of the character described comprising, a screen, said screen including a plurality of concentrically arranged disc-rings, means for rotating the screen, a rim projecting upwardly from the periphery of said screen and being provided with slots, a belt-pulley located outside the circumference of the screen, a belt guided around said rim and said pulley, an endless supply-band for delivering material tangentially onto the screen, and means for driving the said band at substantially the speed of the radial center of one of the said concentric disc-rings.

4. A device of the character described comprising, a screen, said screen including a plurality of concentrically arranged disc-rings, means for rotating the screen, a rim projecting upwardly from the periphery of said screen and being provided with slots, a belt-pulley located outside the circumference of the screen, a belt guided around said rim and said pulley, an endless supply-band for delivering material tangentially onto an inner disc-ring, and means for driving the said band at substantially the speed of the radial center of said inner disc-ring.

5. A device of the character described comprising, a screen, said screen including a plurality of concentrically arranged disc-rings, means for rotating the screen, a rim projecting upwardly from the periphery of said screen and being provided with slots, a belt-pulley located outside the circumference of the screen, a belt guided around said rim and said pulley, an endless supply-band for delivering material tangentially onto an inner disc-ring, another endless supply-band for delivering material tangentially onto an outer disc-ring, and means for driving said bands respectively at substantially the speeds of the radial centers of said inner and outer disc-rings.

6. A device of the character described comprising, a screen, means for rotating the screen about an axis inclined from the vertical, a rim projecting upwardly from the periphery of said screen and being provided

with slots, a belt-pulley located outside the circumference of the screen, and a belt guided around said rim and said pulley.

7. A device of the character described comprising, a screen, means for rotating the screen, means for vibrating the screen, a rim projecting upwardly from the periphery of said screen and being provided with slots, a belt-pulley located outside the circumference 10 of the screen, and a belt guided around said rim and said pulley.

8. A device of the character described comprising, a screen, said screen including a plurality of concentrically arranged disc-rings, 15 means for rotating the screen, means for vibrating the screen, a rim projecting upwardly from the periphery of said screen and being provided with slots, a belt-pulley located outside the circumference of the screen, and a 20 belt guided around said rim and said pulley.

9. A device of the character described comprising, a screen, said screen having its upper surface somewhat dished in shape, means for rotating the screen, a rim projecting upwardly from the periphery of said screen and being provided with slots, a belt-pulley located outside the circumference of the screen, and a belt guided around said rim and said 25 pulley.

10. A device of the character described comprising, a screen, said screen including a plurality of concentrically arranged disc-rings, an inner disc-ring being provided with screen-apertures concentrically disposed and an outer disc-ring being provided with 35 screen-apertures radially disposed, means for rotating the screen, a rim projecting upwardly from the periphery of said screen and being provided with slots, a belt-pulley located outside the circumference of the screen, 40 and a belt guided around said rim and said pulley.

11. A device of the character described comprising, a screen, means for rotating the screen, a rim projecting upwardly from the 45 periphery of said screen and being provided with slots, a belt-pulley located outside the circumference of the screen, a belt guided around said rim and said pulley, and a water spouting device mounted adjacent the periphery of the screen and arranged to direct a stream of water upon the material being sifted and in a direction opposed to the direction of rotation of the screen.

In testimony, that I claim the foregoing 55 as my invention, I have signed my name this 11th day of June 1928.

OTTO WIENCKE.
